US00D980225S

(12) **United States Design Patent** (10) Patent No.: **US D980,225 S**
Cheng (45) Date of Patent: **** Mar. 7, 2023**

(54) **PROTECTIVE CASE FOR ELECTRONIC DEVICE**

(71) Applicant: **Fintie LLC**, Hilliard, OH (US)

(72) Inventor: **Nai Chu Cheng**, Hilliard, OH (US)

(73) Assignee: **Fintie LLC**, Hilliard, OH (US)

(**) Term: **15 Years**

(21) Appl. No.: **29/724,726**

(22) Filed: **Feb. 19, 2020**

(51) LOC (14) Cl. **14-02**

(52) U.S. Cl.

USPC **D14/440; D14/251**

(58) **Field of Classification Search**

USPC D14/440, 447, 250, 432, 439, 251, 253;
 361/679.55; 206/45.23, 320, 45.2;
 294/25; 455/575.8; D3/294

CPC ... G06F 1/1628; G06F 1/1626; A47B 23/044;
 A45C 11/00

See application file for complete search history.

(57) **CLAIM**

The ornamental design for a protective case for electronic device, as shown and described.

DESCRIPTION

FIG. 1 is a front perspective view of a protective case for electronic device, shown in use with a tablet computer and a stylus;

FIG. 2 is a front elevation view of FIG. 1;

FIG. 3 is a rear elevation view of FIG. 1;

FIG. 4 is a right-side elevation view of FIG. 1;

FIG. 5 is a left-side elevation view of FIG. 1;

FIG. 6 is a top plan view of FIG. 1; and,

FIG. 7 is a bottom plan view of FIG. 1.

The broken lines in the drawing figures depict portions of the structure that form no part of the claim.

1 Claim, 5 Drawing Sheets
